UNITED STATES PATENT OFFICE

141,932

DESIGN FOR A HOBBY HORSE

Morris Lecomowitz, Philadelphia, Pa.

Application January 12, 1945, Serial No. 117,388

Term of patent 14 years

(CL. D34—15)

To all whom it may concern:

Be it known that I, Morris Lecomowitz, a citizen of the United States, residing at Philadelphia, in the county of Philadelphia and State of Pennsylvania, have invented a new, original, and ornamental Design for Hobby Horse, of which the following is a specification, reference being had to the accompanying drawing, forming part thereof.

Fig. 1 is a perspective view of a hobby horse showing my new design.

Fig. 2 is a top plan view thereof.

I claim:

The ornamental design for a hobby horse, as shown.

MORRIS LECOMOWITZ.
